UNITED STATES PATENT OFFICE

EDWARD BOSWORTH GRIER, OF WEST HARTFORD, CONNECTICUT, ASSIGNOR TO THE ARROW-HART & HEGEMAN ELECTRIC COMPANY, OF HARTFORD, CONNECTICUT, A CORPORATION OF CONNECTICUT

DESIGN FOR A LIGHTING FIXTURE CANOPY

Application filed March 15, 1933. Serial No. 47,461. Term of patent 7 years.

To all whom it may concern:

Be it known that I, EDWARD BOSWORTH GRIER, a citizen of the United States of America, residing at West Hartford, in the county of Hartford and State of Connecticut, have invented a new, original, and ornamental Design for Lighting Fixture Canopy, of which the following is a specification, reference being had to the accompanying drawing, forming part thereof.

The figure is a perspective view of a lighting fixture canopy, showing my new design.

I claim:

The ornamental design for a lighting fixture canopy or similar article, as shown.

In testimony whereof I have signed my name to this specification.

EDWARD BOSWORTH GRIER.
